UNITED STATES PATENT OFFICE

ERNEST W. HUTTIG, OF DENVER, COLORADO, ASSIGNOR TO COORS PORCELAIN COMPANY, OF GOLDEN, COLORADO, A CORPORATION OF COLORADO

DESIGN FOR AN ASH RECEPTACLE

Application filed March 7, 1931. Serial No. 38,990. Term of patent 3½ years.

To all whom it may concern:

Be it known that I, ERNEST W. HUTTIG, a citizen of the United States, residing at the city and county of Denver and State of Colorado, have invented a new, original, and ornamental Design for Ash Receptacle, of which the following is a specification, reference being had to the accompanying drawings, forming part thereof, in which—

Fig. 1 is a front elevation;

Fig. 2 is a view showing the left side in elevation; and

Fig. 3 is a rear elevation.

I claim:

The ornamental design for an ash receptacle as shown.

In testimony whereof I affix my signature.

ERNEST W. HUTTIG.
